HUMIDIFIER FOR INTERNAL COMBUSTION ENGINES

Filed Nov. 8, 1927

INVENTOR.
EDWARD S. PARRY

BY

W. G. Charles

ATTORNEY.

UNITED STATES PATENT OFFICE

EDWARD S. PARRY, OF TOPEKA, KANSAS

HUMIDIFIER FOR INTERNAL COMBUSTION ENGINES

Application filed November 8, 1927. Serial No. 231,956.

My invention relates to a means to humidify the fuel for internal combustion engines.

The object of my invention is to provide a means that will inject steam or vapor from the radiator into the intake manifold of an internal combustion engine, whereby the mileage is increased with a normal fuel consumption through the medium of my invention herein set forth.

10 A further object of my invention is to provide a valve and controlling means therefor operative from the instrument board of the vehicle, the valve to control the flow through the pipe connecting means of the radiator to the coil.

A still further object of my invention is to provide means to prevent the water from entering the pipe conveying the steam or vapor to the manifold when the radiator is being 20 filled or the water therein unduly agitated.

A still further object of my invention is to provide a housing means to attach the coil to the exhaust manifold and simultaneously protect the coil from external exposure.

25 A still further object of my invention is to provide a baffle means in the pipe to distribute or break up drops of water, should they pass therethrough.

These and other objects will be hereinafter 30 more fully described.

Referring to the drawings:

Fig. 1 is a side view representing an internal combustion engine and its radiator.

Fig. 2 is a fragmentary front end view of 35 the engine, parts removed for convenience of illustration.

Fig. 3 is an enlarged plan view of the hood on the end of the pipe positioned in the radiator.

40 Fig. 4 is an elevation of Fig. 1.

Fig. 5 is a side view of a fragmentary portion of the pipe.

Fig. 6 is a cross section, showing the baffle pins.

45 Like characters will apply to like parts in the different views of the mechanism.

My invention consists of a pipe 1 extending through the radiator 2 and having an upward bend as at 3, by which means the top 50 thereof is positioned above the water line of

the radiator. Positioned on the upper end of the pipe is a hood 4, cylindrical in form and having an aperture 5 in the bottom thereof to receive the pipe snugly. On the upper end of the pipe, concealed by the hood, are legs 6 functioning as spacing means for the top or closed end of the hood from the end of the pipe; the said hood has a plurality of apertures 7 in the side walls thereof as shown in Fig. 4, and also a plurality of apertures 8 55 annularly arranged in the bottom adjacent the pipe, the said apertures function as means by which the steam or vapor rising from the water may enter and be drawn through the pipe and injected into the intake manifold 60 13; the apertures in the bottom function as a drain for condensation or water that may enter through the side apertures when filling the radiator or by undue agitation of the water in the radiator.

Positioned in the upwardly extending portion of the pipe is a cut-off valve 9 having a rod 10 connected thereto and extending rearward through the instrument board 11, and having a handle 12 on the outer end thereof as means by which the valve may be turned by the operator of the vehicle, opening or closing the valve.

The horizontal portion of the said pipe, as at A, extends rearward and being coiled as at B is means by which a greater area of the pipe length may be bound or positioned closely to the exhaust manifold 13 as shown in Figure 1. The outer end of the coil has a transversely positioned bend entering the neck C between the carburetor D and the manifold, by which means the steam or vapor is injected simultaneously with the gas from the carburetor into the cylinders of the engine 14.

It is now readily seen that the vacuum by the downward stroke of the pistons will simultaneously draw fuel from the carburetor and vapor from the radiator through the medium of the pipe 1 and its component parts above described.

As a means to pre-heat the coil of the pipe, a housing 15 is provided as an enclosure for the said coil and binding means therefor, snugly against the side of said manifold. The said housing is securely attached to the 100

manifold by means of straps 16 and 17, the ends of which are attached by bolts 18 and 19. Centrally positioned and laterally extending from the housing is a portion thereof as at F functioning as a guard for a downward extension of the coil as shown in Fig. 1. It will be understood that the peripheral edge of the housing engages snugly on said manifold and being concaved sufficient to receive the pipe coil. Positioned diametrically in the coiled portion of the pipe is a plurality of pins 20, functioning as a baffle or separating means for drops of water passing through the pipe, so that the drops may be more easily vaporized prior to entering the manifold. In Fig. 6 is shown the lower end of the pins aligned in close proximity longitudinally with the pipe and spaced apart similar to that in Fig. 5, the pins being angled in opposite directions alternately. While I have stated that the pins are positioned in the coil, they may be placed as desired along the pipe in groups or equally spaced along the pipe, and being positioned with the lower ends in close alignment is means to insure contact with the drops passing along the lower side of the pipe, as would naturally be the case.

To operate my invention it is preferable to close the valve when starting the engine, and as soon as the engine is properly heated to its normal running temperature the valve may then be opened partially or entirely, at which time the vapor is introduced regularly with the gas mixture as it enters the cylinders of the engine; and the vapor thus applied is beneficial in tending to prevent carbon deposits, as well as increasing the mileage of the gas consumption through the mechanism as designed.

Such other modifications may be employed as lie within the scope of the appended claim.

Having fully described my invention, what I claim as new and desire to secure by Letters Patent is:

In a means to humidify the fuel for an internal combustion engine in combination with the radiator intake manifold and carburetor of an internal combustion engine, a pipe having return bends near one end thereof to function as a heating coil, a housing to clamp the bent portion to the side of the engine's exhaust manifold the adjacent end of the pipe to enter the intake manifold in close proximity to the carburetor, the other end of the pipe projecting through the top portion of the radiator and having an upward right angle bend to extend above the water line in the radiator, a hood positioned on the upper end of the pipe, the hood being tubular and having a plurality of apertures extending through the peripheral wall thereof, the top of the hood being closed and the bottom portion being apertured to receive the end of the pipe snugly and a plurality of apertures spaced apart and being positioned in the bot-

tom between the pipe and the annular wall of the hood, the hood functioning as a baffle against water entering the end of the pipe freely and further functioning as an inlet for humid air into the pipe, a plurality of pins extending through the pipe in close proximity to the bent portion, the pins angling in opposite directions relative to each other as means to stagger the lower ends thereof where they intersect the pipe as means to divert the flow of drops of water passing therethrough, a valve positioned near the upper end of the pipe and a rod attached thereto as turning means therefor, the end of the rod extending rearward and operative from the rear of the engine all as and for the purpose specified.

In testimony whereof I affix my signature.

EDWARD S. PARRY.
